UNITED STATES PATENT OFFICE.

CHESTER J. WELSH, OF CONNEAUT, OHIO, ASSIGNOR TO THE CONNEAUT SHOVEL COMPANY, OF CONNEAUT, OHIO, A CORPORATION OF OHIO.

REINFORCED SPLIT D HANDLE.

Application filed August 26, 1924. Serial No. 734,157.

To all whom it may concern:

Be it known that I, CHESTER J. WELSH, a citizen of the United States, and a resident of Conneaut, county of Ashtabula, and 5 State of Ohio, have invented a new and useful Improvement in Reenforced Split D Handles, of which the following is a specification, the principle of the invention being herein explained and the best mode in which 10 I have contemplated applying that principle, so as to distinguish it from other inventions.

The present invention relates to handles for shovels, spades and other like implements and, as indicated, has more particular regard to handles commonly known as split-D handles wherein the upper end portion of the shaft or stem is split or bifurcated to form two diverging arms between 20 which, at the upper ends thereof, is inserted the grip for the hand of the user. Handles of this type have long been known and are obviously much more economical of material than the ordinary D handle with 25 integral grip which is turned out of the stick of wood from which the shaft of the handle is formed. In such split D handle, in order to firmly secure the grip in place between the two side arms, it has been customary, in addition to passing a bolt or 30 rivet through the parts in question, to provide a metallic reenforcement or cap that fits over the upper end of each arm and engages the adjacent end of the grip, as shown for example in patent to G. C. 35 Howard, Re. No. 1230, dated October 22, 1861. The grip, however, is subjected to a very severe turning moment when the handle is in use and it has been found in 40 practice that such reenforcements as heretofore made do not in general serve to prevent turning of the grip.

The object of the present invention, accordingly, is to provide a handle of this 45 type with an improved form of metallic reenforcement or cap of the sort just referred to which will be effective thus to prevent rotation of the grip. To the accomplishment of the foregoing and related 50 ends, the invention, then, consists of the means hereinafter fully described and particularly pointed out in the claims, the annexed drawing and the following description setting forth in detail certain mechanism embodying the invention, such dis-

closed means constituting, however, but one of various mechanical forms in which the principle of the invention may be used.

In said annexed drawing:—

Fig. 1 is a front elevation of a split-D 60 handle embodying my present improvement, one side of such handle being shown in section; Fig. 2 is a horizontal sectional view of the handle taken on the broken plane indicated by the line 2—2, Fig. 1; Fig. 3 is a 65 vertical transverse section thereof taken on the plane indicated by the line 3—3, Fig. 1; and Fig. 4 is a bottom plan view of one of the reenforcing members.

Only the upper portion of the wooden 70 shaft or stem 1, that carries the shovel, spade or other implement, is shown in Fig. 1, such end being split or bifurcated in the usual manner to present two diverging arms 2. Adjacent the inner ends of these arms 75 2 a rivet 3 is passed through the shaft 1 to prevent further splitting thereof, while between the outer ends of such arms is inserted the transverse grip 4 which is of general cylindrical form in cross-section, being 80 turned from a suitable piece of wood. As shown, such grip is slightly arcuate in shape when viewed from the front, but this is not essential to the invention which, as previously indicated, relates to the metallic 85 reenforcements or caps 5. Each of the latter is in the form of a hollow shell shaped to fit over the upper end of one of the side arms 2 and to encircle the adjacent end of the grip 4. Such end is turned down so as to 90 present a shoulder 6 against which the cap piece abuts and the lower face 7 of such reduced grip end is furthermore flattened transversely, as best shown in Fig. 3. It will be noted that the inner portion of the 95 cap piece 5 projects beyond the inner face of the corresponding side arm 2 and constitutes in effect an annulus or ferrule 5^a that completely encircles the adjacent reduced end portion of the grip. The under portion 5^b of this annulus or ferrule is flattened to correspond with the flat face 7 on the grip and as a result the grip will obviously be held against rotation within the cap piece. The latter is fitted sufficiently 100 tightly on the upper end of arm 2 to be held firmly against rotation thereon, consequently the grip is positively secured against any movement with respect to the 105 two arms of the handle. A rivet or bolt 8 110

is passed through the cap pieces 5, the ends of the corresponding arms 2, and the interposed grip so as to bind or tie the parts firmly together.

5 As a result of the foregoing construction, a very strong and substantial handle of the split-D type is provided and as just pointed out, all danger of the grip turning between the two side arms of such handle is practically eliminated. It will be understood that in use, implements of the class in question are necessarily exposed more or less to the weather and no matter how tightly the ferrules of the cap pieces may be initially 10 fitted onto the adjacent ends of the grip, the latter will in time tend to work loose where the ferrule portion is merely annular in form. No special nails or extensions of the cap pieces are involved in the present 15 improved construction, the cap pieces or metallic reenforcements being, if anything, smaller in size than heretofore employed for this purpose.

Other modes of applying the principle of 20 my invention may be employed instead of the one explained, change being made as regards the mechanism herein disclosed, provided the means stated by any of the following claims or the equivalent of such 25 30 stated means be employed.

I therefore particularly point out and distinctly claim as my invention:—

1. In a handle of the type described, the combination with a shaft bifurcated at its upper end to form diverging arms; a grip bar inserted between such arms; and a reinforcing member for each of the latter comprising a cap encasing the upper end of the arm and a portion surrounding the adjacent end of said grip bar, such surrounding portion and grip bar end having registering non-circular parts, whereby said bar is locked against rotation. 40

2. In a handle of the type described, the combination with a shaft bifurcated at its upper end to form diverging arms; a grip bar inserted between such arms; and a reinforcing member for each of the latter comprising a cap encasing the upper end of the arm and a portion of generally annular form surrounding the adjacent end of said grip bar, such end being reduced to receive such annular portion and the latter and such end being flattened in corresponding parts, whereby said bar is locked against 45 50 55 rotation.

Signed by me, this 23d day of August, 1924.

CHESTER J. WELSH.
